ABSTRACT OF THE DISCLOSURE

A fixture for displaying articles, such as letters, house numbers, and signs, although it may be utilized to display other merchandise, such as rings, trinkets, pins, Christmas cards or bulbs, or other ornaments which fixture may be suspended from a Peg Board or supported on a table or counter. The fixture includes an upwardly extending rod or bar and a horizontal bar secured as by welding thereto. The horizontal rod or bar in turn has horizontal portions at each end integral therewith or welded thereto which horizontal portions terminate in vertical end portions or which have vertical portions secured to each end. The fixture may be turned to insert the vertical portions formed integral with or secured to the horizontal rod or bar through openings in the Peg Board. The fixture is then released at which time the horizontal portions rest on the Peg Board.

The fixture may be supported on a counter or table and includes in addition to the rear rod or bar, a pair of spaced rods having cushioned shoes resting on a counter or table and an upwardly extending front bar or rod on which a plurality of trays may be supported which trays are spaced from and are independently rotatable relative to each other. The inner end portion of fingers are welded to the lower portion of each tray and have upwardly turned outer end portions for supporting house numbers, letters and signs although the fingers may be utilized for supporting other articles, such as trinkets, rings, or ornaments. Cards, pins, or ornaments may also be supported on each tray.

Our invention relates to a fixture for displaying house numbers, letters, and signs, although it may be utilized for displaying jewelry, trinkets, and ornaments, and more particularly to a fixture of this type that may be suspended from a Peg Board or supported on a counter or table.

In retail stores dealing in house numbers, letters, and signs, and other merchandise, such as rings, trinkets and particularly ornaments, such as pins, Christmas tree bulbs, or cards, which sell at a comparatively low price, it is desirable to provide a compact fixture for displaying a large number of such articles.

It is an object of the present invention to provide an improved fixture for displaying house numbers, letters and signs, although it may be utilized for displaying other merchandise, such as jewelry, rings, trinkets, pins and ornaments of various types which fixture may be suspended from a Peg Board or supported on a counter or table.

Another object of our invention is to provide an improved fixture including a plurality of trays, each of which is independently rotatable so that house numbers, letters, signs or other merchandise, such as ornaments or trinkets resting or supported thereon may be conveniently displayed to prospective customers.

A further object of our invention is to provide a display fixture, including a plurality of spaced trays forming a support for articles, such as house numbers, letters, or other merchandise, such as rings, trinkets, pins, bulbs, and like ornaments, in which each tray is provided with a plurality of spaced fingers, each of which is shaped to

2

support an individual item, such as a letter or number, although they may be utilized for displaying other merchandise, such as a ring, trinket, or other ornament having an opening through which one of the fingers may be inserted.

Our invention will be better understood by reference to the accompanying drawings in which:

FIG. 1 is an exploded view of one form of our improved fixture;

FIG. 2 is a cross sectional view taken on a plane passing through the line 2—2 of FIG. 1;

FIG. 3 is a plan view and FIG. 4 is a side elevational view of one of the trays;

FIG. 5 is a plan view and FIG. 6 is a side elevational view of another tray;

FIG. 7 is an elevational view of the assembled fixture shown in FIG. 1;

FIG. 8 is an exploded view of another form of our invention;

FIG. 9 is a cross sectional view taken on a plane passing through the line 9—9 of FIG. 8;

FIG. 10 is a plan view and FIG. 11 is a side elevational view of one of the trays shown in FIG. 8;

FIG. 12 is a plan view and FIG. 13 is a side elevational view of the other tray shown in FIG. 8; and

FIG. 14 is a perspective view of the fixture shown in FIG. 8 with the parts assembled in place.

One of our improved fixtures is shown in FIGS. 1 to 7 which may be suspended from a Peg Board 1 or supported on a counter or table 2. As illustrated in the drawings, the fixture comprises a U-shaped rod or bar including a vertical portion 3, a forwardly extending upper arm 4 which terminates in a flat portion 5, and a forwardly extending lower arm 6 which terminates in a flat portion 7.

For supporting the fixture upon Peg Board 1 which has a plurality of apertures therein, a bar 8 extends horizontally along and is secured centrally to the upper end portion of the vertical bar 3. The bar 8 is provided with angularly-shaped members 9 and 10 adjacent each end portion, each of which consists of a downwardly extending arm 11 secured as by welding to the face of bar 8 and a portion 12 which extends horizontally above bar 8 and which terminates in a substantially vertical portion 13.

When suspending the fixture from the Peg Board, the U-shaped rod is moved to a position in which the end portions 13 of the angularly-shaped members extend at an angle of approximately 90° to the Peg Board at which time they may be inserted in aligned openings therein. The U-shaped bar is then released at which time it assumes the position shown in FIG. 2 in which it is supported by the horizontal arms of the angularly-shaped members. The Peg Board may be secured in spaced relation to the wall of the store in any convenient manner, such as by nails or screws forced through the board and suitable spacers, not shown.

To enable the fixture to be supported on a counter or table, a rod 14 is secured centrally thereof by suitable means, such as welding, to the bar 3 and has downwardly turned end portions provided with cushion shoes 15 which rest on the table or counter and the central portion of a rod is welded or otherwise secured to the front portion of the bar 6 which is provided with arms 16 and 17 extending outwardly at an angle of approximately 90° to each other and each of which is turned downwardly and is provided with a shoe 18 formed of a cushioning material which rests upon the table or counter.

In accordance with our invention, means are provided for supporting a plurality of trays, each of which may be rotated independently of each other upon the front rod of the fixture. For this purpose, the flat portions 5 and 7

of arms 4 and 6 have apertures therein to receive a rod 19, the lower portion of which may be provided with a cushioning shoe which is supported on the counter or table, and means associated with the rod 19 and the lower flat portion 7 of bar 6 are provided for supporting a plurality of trays in spaced relation. While the number of trays supported by each fixture may vary and we do not desire to be limited in this respect, as shown in FIG. 1, four trays 20, 21, 22 and 23 are provided, each of which has a central opening therein to receive the rod 19.

As shown in FIG. 1, rod 19 extends through apertures in the flat portion 7 of the lower arm and the flat portion of the upper arm 16 and is held in place by set screws 24 and 25. When set screws 24 and 25 are released, however, rod 19 may be lowered to a position in which its upper end is in alignment with the upper surface of the flat portion 7 of bar 6 at which time tray 23 may be spaced upwardly from the flat portion of rod 6. For this purpose a spacer 26 is provided having upper and lower flanges 27 and 28, the upper flange 27 having an aperture therein in alignment with the central opening in tray 23 which flange extends beyond its opening to provide a brace for tray 23 to which it may be secured as by welding. The lower flange 28 also has an opening therein which is in alignment with the aperture in the flat portion 7 of bar 6. In assembling the device, rod 19 is moved upwardly through the apertures in flanges 28 and 27 and the central opening in tray 23.

In a like manner, a tray 22 is provided with a spacer 29 including an upper flange 30 having an opening therein which is in alignment with the opening in tray 22 and which extends beyond its opening and is secured as by welding to and provides a brace for tray 22. Spacer 29 also has a lower flange 31 having an opening therein which is arranged in alignment with the openings in trays 22 and 23. After passing through flanges 28 and 27 and tray 23, rod 19 is moved upwardly through the openings in flanges 31 and 30 and tray 22.

For spacing tray 21 from tray 22, a spacer 32 is provided having an upper flange 33 with an opening therein which is in alignment with the central opening in tray 21 and which flange extends beyond its opening and is secured as by welding to and serves to support tray 21. The spacer 32 is also provided with a lower flange 34 having an opening therein which may be arranged over tray 22 in alignment with the opening therein to receive rod 19 as rod 19 is moved upwardly through the openings in flanges 34 and 33 and tray 21.

Similar means is provided for spacing tray 20 from tray 21. As shown, a spacer 35 is provided having an upper flange 36 secured as by welding to the lower face of tray 20. As shown, flange 36 has an opening arranged in alignment with the opening in tray 20 and a portion extending beyond its opening for supporting tray 20 which is secured thereto by welding. The spacer 35 also has a lower flange 37 having an opening therein which may be arranged in alignment with the opening in tray 21. The rod 19 may therefore be moved upwardly through the apertures in flanges 37 and 36 and the central opening in tray 20 at which time it may be held in place by the upper and lower set screws 24 and 25.

The trays may be circular in shape or as shown in FIG. 5, provided with a plurality of short sides. One end of each of a plurality of spaced fingers 38 is also secured as by welding to the underside of each tray which fingers terminate in upwardly turned portions upon each of which a house number, a letter, or other merchandise, such as a trinket, a pin, ring, or a Christmas tree ornament may be mounted. Because the upper flange of each spacer is secured to the lower face of one of the trays, it is apparent that each tray may be rotated relative to the other trays for conveniently displaying all the letters and house numbers or other merchandise, such as trinkets or ornaments to prospective customers. For instance, tray 21 may be held in place while tray 20 is rotated. In the construction shown, it will be apparent that cards, such as Christ-

mas, Easter, or other cards, may be deposited on the trays and house numbers, letters and other merchandise, such as rings and pins may be hung on the fingers. Additional fingers 39 which are comparatively long may also be secured to bar 8. When the trays are utilized for supporting house numbers and letters, the trays carrying the larger number of fingers may be utilized for the letters and the trays having the smaller number of fingers may be utilized for supporting the numbers and a sign with letters and numerals in place may be interposed between the fingers 39.

Another form of our fixture is shown in FIGS. 8 to 14 which is somewhat similar to the fixture shown in FIGS. 1 to 7 in that the fixture may be suspended from a Peg Board or supported upon a counter or table. For suspending the fixture from a Peg Board, the fixture includes a vertical rod or bar 40 to the upper portion of which is secured as by welding a horizontal rod or bar 41, the opposite end portions of which are turned inwardly toward the Peg Board as indicated by the numeral 42 and extend through spaced apertures therein. The inwardly turned end portions then extend upwardly as indicated by the numeral 43. In suspending the fixture from the Peg Board, it may be turned to a position in which the upwardly extending end portions 43 of rod 41 are perpendicular to the Peg Board. The fixture is then turned to its normal vertical position at which time the horizontal portions 42 of rod 41 rest on the Peg Board at the openings therein. For supporting the device on a counter or table, a horizontally extending rod 44 is provided which is secured centrally thereof to the lower portion of bar 40 and is turned downwardly at its opposite ends to provide legs 45 which are provided with a cushioned shoe 46 on each leg.

To provide a base for supporting a plurality of trays, each having a central aperture therein, rod 40 is turned forwardly at a short distance below rod 44 as indicated by the numeral 47 and is supported at its free end by the central portion of a rod 48 having downwardly turned legs 49 which as shown are provided with cushioned shoes 50.

The number of trays may of course be varied depending upon the size of the fixture. As shown, two trays 51 and 52 are provided and means associated with the longitudinal rod 47 and a vertical rod 53 are provided for supporting the trays and spacing the lower tray from rod 47 and the trays from each other. For this purpose, a lower spacer 54 has a flange 55 at its upper portion which is secured as by welding to the tray 52 and is provided with an aperture which is arranged in alignment with the aperture in the tray. Flange 55 extends beyond the aperture to form a firm support for tray 52. The spacer 54 also has a flange 56 at its lower portion which is in alignment with the openings in tray 52 and flange 55. In assembling tray 52 on the rod 53, the tray 52 and the spacer 54 are lowered with their apertures in alignment with rod 53 to move the flange 56 downwardly into engagement with rod 47 at which time rod 53 extends through the apertures in flanges 56 and 55 and the lower tray 52.

To space tray 51 from tray 52, a spacer 57 is provided having an upper apertured flange 58 which aperture is in alignment with the aperture in tray 51. As shown, flange 54 extends outwardly beyond its aperture and is secured as by welding to the underside of tray 51 to provide a firm support for the tray. Spacer 57 is also provided with a lower flange 59 having an aperture therein which is in alignment with the apertures in flange 58 and tray 51.

The trays may be round or they may be provided with a plurality of sides. As shown in FIGS. 8 to 14, they are in the form of polygons having five sides and in addition to the surface of each tray, fingers are provided for supporting house numbers, letters, and other merchandise, such as rings, trinkets or ornaments. The inner end of each of the fingers is secured as by welding to the lower surface of each tray and the outer end of each of which

5

is turned upwardly to provide a support for letters, numbers, or other merchandise. As shown in the drawings, each tray may be rotated independently of the other tray to conveniently present each article on the tray or suspended therefrom to prospective customers. When the fixture rests upon a table or counter, it will of course be understood that the rod which is secured to the rear vertical bar and the projections at each end portion thereof, both in the structure shown in FIGS. 1 to 7 and FIGS. 8 to 14 may be utilized to support ornaments, beads, or religious articles, such as rosaries.

What we claim is:

1. A display fixture including a front bar, means for supporting said bar in a substantially vertical position, a plurality of trays rotatably mounted on said bar, and means associated with said bar for supporting said trays in spaced relation to each other, each of which supporting means is slidable on said bar and each of which has a flanged upper end portion secured to one of the respective trays and a lower portion rotatable on said bar.

trays and a lower portion rotatable on said bar.

2. A display fixture as defined in claim 1 in which each of said trays has an outer peripheral portion and a flat lower face portion, and a plurality of angularly-shaped fingers associated with each tray, each of which fingers has its lower end portion secured to the lower face portion of one of the respective trays and each of which fingers first extends radially outwardly and then upwardly beyond the peripheral portion of the tray to which it is secured to form a support for articles placed thereon or attached thereto.

3. A display fixture as defined in claim 1 including an upwardly extending rear bar, a stationary board having spaced aligned apertures therein, a longitudinally extending bar secured to said rear bar and angularly-shaped means for supporting said display fixture secured to the opposite end portions of the horizontally extending bar, each of said angularly-shaped supporting means having a longitudinal portion extending through one of a pair of spaced aligned apertures in said board and each having a portion extending upwardly along the rear wall of said board with its horizontal portion resting upon the board at the aperture through which it extends.

4. A display fixture as specified in claim 3 in which forwardly extending fingers are secured to the opposite end portions of said horizontally extending bar for supporting a sign.

5. A display fixture as defined in claim 1 in which the means for supporting the front bar includes a rear bar, a lower horizontal bar extending forwardly from the rear bar to which the front bar is connected, and means for supporting said fixture in a position for displaying articles supported thereon including a rod secured to the rear bar and having downwardly extending legs and a second rod

6

secured to the lower horizontal rod adjacent its front end portion and having downwardly extending legs.

6. A display fixture as defined in claim 1 in which the upper flange of each of said spacing means is comparatively long and is secured to the lower face of a tray to form a support therefor.

7. A display fixture as defined in claim 1 in which each of the trays has a central opening therein and each of the tray supporting means has upper and lower flanges having aligned openings therein which openings are also in alignment with the opening in each of said trays and in which the front bar extends through the central opening in each of said trays and through the aligned openings in each of the flanges of each of said tray supporting means.

8. A display fixture as defined in claim 1 in which the means for supporting the front bar includes a rear bar and a lower horizontal bar extending therefrom and in which each of the trays has a central opening therein and

each flange of each of the tray supporting means has an opening therein which is in alignment with the opening in the other flanges and the openings in each of the trays, and in which the front bar extends through the central opening of the tray and the alignment opening in the flange.

opening in each of the trays and the aligned openings in the flanges of the tray supporting means and in which the
25 upper flange of each tray supporting means is connected to the bottom face portion of a tray and the lower flange of one of the tray supporting means rests upon the lower horizontal bar and is rotatable around the front bar and the lower flange of each of the other spacing means rests
30 upon one of the respective trays and is rotatable around the front bar.

the front bar.

9. A display fixture as defined in claim 8 including a horizontal bar extending from the upper portion of the rear bar and terminating in a flat portion having an opening therein and in which the lower horizontal bar terminates in a flat portion having an opening therein, said front bar extending through the aligned openings in the flanges of the tray supporting means and the central openings in the trays, and the openings in the flat portions of the upper and lower horizontal bars, and releasable means for securing the front bar to the upper and lower horizontal bars.
